GLAZIER'S POINT DRIVER

Chester K. Judd, Jr., Bristol, Conn., assignor to The Fletcher-Terry Company, Forestville, Conn., a corporation of Connecticut

Application November 28, 1955, Serial No. 549,251

5 Claims. (Cl. 1—44)

This invention relates to a glazier's point driver and more particularly to a hand operated device for dispensing and driving glazier's points into a window sash or the like to hold panes of glass therein.

An object of the present invention is to provide such a device which is highly efficient in its operation and which can be economically produced in large quantities.

A further object of this invention is to provide such a device which is easy to use and to refill with points when necessary.

Further objects and advantages of this invention will be more clearly understood from the following description and the accompanying drawings in which:

Fig. 1 is a plan view of a glazier's point driver embodying my present invention.

Fig. 2 is an enlarged sectional end view thereof on line 2—2 of Fig. 3, but with the point magazine removed.

Fig. 3 is a side view of said device.

Fig. 4 is an end view thereof.

Fig. 5 is an enlarged sectional side view of the front portion of said device showing the parts thereof in normal position.

Fig. 6 is a similar view showing the parts in point driving position.

Fig. 7 is a sectional end view on line 7—7 of Fig. 5.

Fig. 8 is an isometric view of the combined point driver and return spring member.

Fig. 9 is a plan view of the anchoring member.

Fig. 10 is a plan view of the carrier member.

Fig. 11 is a bottom view of said carrier member.

As illustrated in the drawings, my improved device includes a frame 5 which is preferably formed of round wire and includes an upwardly inclined U-shaped handle portion 6 and a base portion 7; the said base portion consisting of a pair of spaced parallel prongs 8—8 which project forwardly from the portion 6.

An anchoring member 9 extends across said prongs and consists of an elongated bar 10 having inverted U-shaped end portions 11—11 which extend over the prongs and are preferably spot welded thereto, as indicated at 12—12, to secure the said anchoring member to the prongs. The bottom surface of said member is substantially on a plane with the bottom surfaces of the prongs, and the central portion thereof is bent upwardly, as at 13, to provide a channel thereunder and has an opening 14 therein. The anchoring member 9 carries a combined point driver and return spring which is constructed of flat spring stock and includes a driver 15, that is riveted to the underside of the said portion 13, and an inverted U-shaped return spring portion 16, one leg of which extends upwardly through the said opening 14 and the other leg having a free end portion 17 bent forwardly therefrom.

The said anchoring member 9 is disposed rearwardly of the free end portions of the prongs 8—8, and a carrier member 18 extends across said end portions of the prongs. The said carrier member consists of an upper

2

plate 19 having inverted U-shaped end portions 20—20, in which slidably fit the end portions of the prongs 8—8, and lower plate portions 21—21 which extend inwardly from the U-shaped portions and under the said prongs 5 and the central portion of said upper plate 19, as clearly illustrated in Fig. 2. The central portion of said upper plate is bent upwardly, as at 22, to provide a centrally located passage through the carrier member which is in alignment with the channel that is formed under the upwardly bent portion 13 of the stationary anchoring member 9. As shown in Fig. 11, one of the lower plate portions 21 of the carrier member 18 has an extension 23 which projects into a notch in the opposite plate portion 21 to strengthen the bottom of said carrier member.

The driver 15 is secured against the bottom of the raised portion 13 and extends forwardly therefrom into the said passage 24, as clearly illustrated in Fig. 5. The front portion of the said driver has a V-notch 25 therein to conform with the shape of the glazier's points that are used with said device.

The upwardly bent portion 22 (Fig. 6) of the carrier member has an upwardly extending lip 26 which provides an abutment for anchoring the free end 17 of the return spring portion 16, and the said raised portion also 25 has a hole 27 therein, shaped like the glazier's points, but slightly larger, which is adapted to receive the lower end of a stack of points 28 which are adhered together by a suitable adhesive that is adapted to release only the bottom point from the stack as it is being driven by the device.

The upper plate 19 (Fig. 2) and the lower plates 21—21 of the carrier member are secured together by a pair of vertical posts 29—29 which extend upwardly from the carrier member 18, at opposite sides of the portion 22, and 35 provide a support for a tubular magazine 30 which has a central portion 31, that conforms to the shape of the points, and tubular side portions 32—32 extending therefrom which fit over the said posts 29—29 so that the said magazine is slidable thereon and may be removed by 40 raising it off said posts.

In order to force the said stack of points downwardly, I provide an inverted U-shaped spring member 33 having one end thereof preferably anchored upon the anchoring member 9 by a rivet 34. Its opposite end is freely 45 movable and extends downwardly into the magazine 30 and has a loop 35 at its end which engages the top of the stack of points.

The carrier member 18 has slots 36—36 in its opposite sides which receive projections 37—37 extending from 50 the prongs 8—8 that engage the ends of said slots and slidably retain the said carrier member on the prongs.

In the use and operation of my improved device, the stack of points 28 is first placed in the tubular magazine 30 so that the bottom of said stack extends into the hole 55 27 and rests upon the bottom of the passage 24, directly in front of the driver 15 and partly within the notch 25 therein. The free end of the spring member 33 is then inserted into the magazine and allowed to press upon the top of the stack of points and the device is ready for 60 use.

When it is desired to drive the said points into a window sash 38, or the like, the device is simply held by the handle 5 and the carrier member 18 is placed on the surface of the glass and against the side of the sash. The handle 5 is then forced towards the sash and this will move the member 9 and driver 15 forwardly relatively to the carrier member 18 causing it to pick up the bottom point in the stack 28 within the notch 25 and force said point forwardly, through the passage 24 and into the sash, as illustrated in Fig. 6. The device is then moved away from the sash and the spring 16 will return it to its normal position shown in Fig. 5.

I claim:

1. A glazier's point driver including a carrier member, a wire frame having a handle portion and a pair of parallel prongs extending forwardly therefrom and having their free end portions slideable in said carrier member, an anchoring member extending across said prongs inwardly of their free ends and secured to said prongs, said carrier member having an elongated passage extending therethrough and a hole therein communicating with said passage, a driver secured to the anchoring member and extending into said passage to a point adjacent said hole, means for retaining a stack of points in vertical position and in said hole with the bottom point of the stack resting upon the bottom of said passage, a spring anchored on one of said members and having a free end portion in engagement with an abutment on the other member, and a separate inverted U-shaped spring having one leg secured to one of said members and the other leg engaging the top of the stack of points for forcing it downwardly into said hole.

2. A glazier's point driver as set forth in claim 1 wherein said retaining means includes a pair of posts extending vertically from the carrier member at opposite sides of the said hole, and a magazine slidably mounted over said posts for guiding the stack of points into the hole.

3. A glazier's point driver including a carrier member, a frame constructed of wire and formed to provide a handle portion having a pair of parallel prongs extending forwardly therefrom and having their free end portions slideable in said carrier member, an anchoring member extending across the prongs inwardly of the free end portions thereof and secured thereto, the said carrier member having an elongated passage therethrough extending substantially parallel to said prongs and having a hole communicating with said passage through the top of said carrier member, a combined driver and spring member having a driver portion secured to the anchoring member and extending forwardly therefrom into said passage with its free end normally disposed rearwardly of said hole and having a notch therein to receive the points and an inverted U-shaped portion extending upwardly therefrom and providing a spacing having a free end in engagement with an abutment on the carrier member for yieldingly urging the said anchoring member rearwardly relatively to the carrier member, a magazine on said carrier member adapted to guide a stack of points into said hole, and spring means extending downwardly into said magazine and engageable with the top of a stack of points therein for urging the said stack downwardly into the hole.

4. A glazier's point driver including a carrier member, a frame constructed of a piece of wire formed to provide a handle portion and a pair of parallel prongs extending therefrom and having their free end portions slideable in said carrier member, an anchoring member extending across said prongs and secured thereto rearwardly of the free end portions of said prongs, means for yieldingly retaining the said anchoring member spaced rearwardly of

the carrier member, the said carrier member having an elongated passage therein and a hole communicating with said passage through the top of the carrier member, means on said carrier member for retaining a stack of points in vertical position with the bottom of the stack extending through the hole and resting upon the bottom of the elongated passage, an inverted U-shaped spring having one leg anchored upon one of said members and its other leg adapted to engage the top of the stack of points and force it downwardly against the bottom of said passage, and a driver member secured to said anchoring member and movable forwardly in said passage to drive the bottom-most point of the stack into a sash or the like.

5. A glazier's point driver including a carrier member, a frame constructed of a piece of wire and formed to provide a handle having a pair of angularly disposed spaced parallel prongs extending forwardly therefrom and having their free end portions slideable in said carrier member, means for slidably retaining said free end portions of the prongs in said carrier member and normally locating them rearwardly wherein their free ends are spaced from the front edge of the carrier member, the said carrier member consisting of an upper plate portion having upwardly extending loops across the opposite ends thereof to slidably receive the said prongs, a raised central section having a hole therethrough and lower plate portions extending from the said loops against the bottom of said upper plate portion and under the said raised section and thereby forming an elongated passage in said carrier member communicating with the said hole, an anchoring member extending across said prongs rearwardly of said carrier member and having inverted U-shaped loops at its opposite ends fitting over the prongs and secured thereto, the central portion of the anchoring member having an upwardly bent section forming a channel in the bottom thereof in alignment with the passage in the carrier member, a member secured in the said channel of the stationary member and having a driver portion projecting therefrom into the said passage of the carrier member to drive said points and an inverted U-shaped spring portion having one leg continuing upwardly from said driver portion and a free leg in engagement with an abutment on the other member for yieldingly urging the anchoring member rearwardly into normal position, a magazine positioned over said hole, and an inverted U-shaped wire spring having one leg anchored and the other leg extending downwardly into the said magazine and engaging the top of a stack of points therein and forcing said stack downwardly through the hole into said passage.
